The ornamental design for a hose fitting, as shown and described.

DESCRIPTION

FIG. 1 is a perspective view of a hose fitting; FIG. 2 is a front view of the hose fitting of FIG. 1; FIG. 3 is a rear view thereof of the hose fitting of FIG. 1; FIG. 4 is a side view of the hose fitting of FIG. 1 (as taken from the left of FIG. 2); FIG. 5 is a side view of the hose fitting of FIG. 1 (as taken from the right of FIG. 2); FIG. 6 is a top view of the hose fitting of FIG. 1; and, FIG. 7 is a bottom view of the hose fitting of FIG. 1. The broken lines shown in the drawings depict portions of the hose fitting that form no part of the claim.
